UNITED STATES PATENT OFFICE

2,097,903

DIAPER

Clarissia Wallis, Chicago, Ill.

Application December 26, 1935, Serial No. 56,153

2 Claims. (CL 128—284)

This invention relates to improvements in diapers.

An object is to provide a simple, practical, and inexpensive article of the character described.

5 Another object is to provide a diaper adapted to remain dry on the outside for a long period of time after the inside may have become wet.

Another object is to provide a diaper adapted to prevent chilling of the wearer.

10 A further object is to provide a diaper adapted to have an unusually large moisture absorption capacity.

Other related and incidental objects and advantages will appear and be brought out more fully from the following description, reference being had to the accompanying drawing, wherein:

Fig. 1 is an open view of a preferred embodiment of my invention, presenting the inner side thereof;

20 Fig. 2 is a cross-section of the same, taken along the line 2—2 of Fig. 1;

Fig. 3 is a view similar to Fig. 1, with the outer side uppermost and showing the component parts 25 partially separated;

Fig. 4 is a view of an extra layer of material used in connection with my invention;

Fig. 5 is a view of the moisture resisting sheet employed in my invention;

30 Fig. 6 is a cross-sectional view, taken along the line 6—6 of Fig. 1;

Fig. 7 is a partial sectional view, taken along the line 7—7 of Fig. 1;

Fig. 8 is a sectional view, taken along the line 35 8—8 of Fig. 1; and

Fig. 9 is a perspective view illustrating the invention in use.

Referring more particularly to the drawing and particularly to Fig. 1, I show a diaper having the 40 general outline indicated, consisting essentially of sheet material having a front body portion 15 and back portion 16. The diaper has an inside member 17 preferably having the form indicated and an outside member 18 substantially identical in 45 outline to the inside member 17. Members 17 and 18 are each provided with elongated portions 19 adapted to constitute waistbands to be brought around the front of the body of the wearer and secured together in any suitable manner as will be 50 obvious. The members 17 and 18 are provided with cut-out portions 20 adapted to accommodate the legs of an infant utilizing the invention, and the edge portions of members 17 and 18 are secured together as by inside stitching, which 55 continues entirely around the edges of the said

members with the exception of a portion at the top of the back between the letters A A in Fig. 1 and also at the base of each recess 20 between the points marked B B, respectively, in Fig. 3.

The construction as defined so far results in a 5 flat and somewhat hollow article, wherein additional sheet material about to be described may be inserted. In Fig. 4 I show an extra layer 21 preferably of flannel or similar material having the outline indicated which is preferably smaller 10 in area than that of the members 17 and 18. The layer 21 is provided with cut-out portions 22 similar in shape to cut-outs 20, and the layer 21 is secured as by stitching 23 to the inside of the inside member 17 as will be clear from Figs. 1 and 15 3, the cut-out portions 22 being found to register with cut-outs 20, layer 21 serving essentially as an auxiliary member to provide the inner member 17 with a double thickness and substantially doubling the moisture absorption capacity of the 20 same.

In Fig. 5 I have shown a moisture resisting layer of sheet material which may be of rubber or a rubberized fabric formed substantially as shown and having a generally similar shape to 25 members 17 and 18, and adapted to be inserted between the outside member 18 and member 21, which as hereinbefore stated, is secured to the inner side of inside member 17. Sheet 24, however, has abbreviated portions 19c which are 30 adapted to extend partway into the space formed by the members 19 to insure the layer 24 remaining flat and extended at all times, and the sheet 24 is provided with cut-outs 25 adapted to register substantially with cut-outs 20 and 22 but having inside edge portions 25d of less depth than the base of cut-outs 20 and 22, the edge portions 25d being adapted to extend or protrude outside of the envelope formed by members 17, 18, and 21 for a purpose to be presently disclosed. Sheet 24 is 40 further provided with an extending edge portion 26 adapted to extend downwardly beyond the outer edge of members 17, 18, and 21 at the upper portion of the back, the edges 25d and 26 extending outwardly from within the envelope at the 45 places as mentioned above where the stitching of member 17 to 18 was discontinued.

In Fig. 9 the diaper is shown in place upon the body of an infant, the waistband portions 19 being brought around to the front and secured 50 together as by pinning, the portions 25d of the rubber sheet 24 being shown extending out from within the envelope and adapted to lie against the leg of the infant. In a similar manner the edge 26 of sheet 24 extending outwardly from 55

within the envelope, will lie across the back of the infant. By the arrangement just described it will be found that a double thickness of flannel material is immediately in contact with the body of the infant, the rubber sheet 24 being outside of the same and the outside member 18 being outside of the sheet 24. When the inside members 18 and 21 become wet the rubber layer 24 will prevent the outside member 18 from becoming wet, the portions 25d and 26 assisting greatly to this end in case of an excess of moisture tending to run out at these points by forming a seal with the body of the infant at these places, thus retarding and resisting the moisture and preventing it from being absorbed by the outside member 18, a time interval occurring therein sufficient for the inside members 17 and 21 to absorb this moisture.

It has been found that in use the diaper as hereinabove described, will remain dry on the outside for an indefinite period even after the inside portion has become nearly saturated, and that further, evaporation of the moisture is practically prevented by the rubber layer 24, the effect of which is that the body of the infant will not become chilled or cold incidental to such ordinary evaporation.

While I have illustrated and described the preferred form of construction for carrying my invention into effect, this is capable of variation and modification without departing from the

spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A device of the character described comprising an outer layer and inner layer, and means to prevent the outer layer from becoming moist upon the moistening of the inner layer, said means including a moisture resisting element, and a second layer secured to said inner layer, said layers and elements having registering leg 15 cut-out portions, said moisture resisting element cut-out being of less depth than the cut-out portions of said layers.

2. A diaper as described, comprising inner and outer absorbent layers, said layers having leg 20 cut-out portions at the side thereof, and means to prevent the outer layer from becoming moist upon the moistening of the inner layer, said means including a non-absorbent element between said layers, the side edges of said element 25 being adapted to extend outside of and partially across the said leg cut-outs and adapted to adhere to the body of the wearer upon becoming moist.
